UNITED STATES PATENT OFFICE.

DONALD BARNS MORISON, OF HARTLEPOOL, ENGLAND.

AIR-EJECTOR.

1,055,210.

Specification of Letters Patent.

Patented Mar. 4, 1913.

Original application filed April 29, 1910, Serial No. 558,329. Divided and this application filed September 29, 1910. Serial No. 584,518.

To all whom it may concern:

Be it known that I, DONALD BARNS MORISON, a subject of the King of Great Britain and Ireland, residing at Hartlepool, in the county of Durham, England, have invented Improvements in or Relating to Air-Ejectors; of which the following is a specification.

This invention has reference to improved constructions of air ejector of the kind worked by the aid of water supplied thereto under pressure, or of water and steam, and suitable for use in connection *inter alia* with steam condensing and vacuum producing apparatus of the kind for example described in the specification of another application for Letters Patent filed by me April 29th, 1910, Serial No. 558,329, of which the present application is a division, whereby the scope and usefulness of such apparatus can be increased.

An air ejector suitable for the purpose mentioned, comprises a water spraying device and a water jet device arranged in series or in parallel with each other, or a water spraying device and a water jet device arranged in parallel with each other and in series with a final water jet device, or a steam nozzle with a water spraying or condensing device and a water jet device arranged in series or in parallel with each other, or with a water spraying device and a water jet device arranged in parallel with each other and in series with a final water jet device, and means whereby the flow of fluid through the water jet devices and the steam nozzle, when used, can be severally controlled to suit varying working conditions.

In the accompanying drawings, Figures 1 and 2 show, in vertical section, two constructions of air ejector embodying the present invention, together with a tank into which the ejector discharges, and a pump for circulating water between the ejector and tank.

As the air ejector is specially adapted for use with a steam engine condenser for withdrawing air and vapor therefrom, it will be now described in connection with such a condenser but it is to be understood that its use is not limited to a condenser as it may be used in connection with other vessels or devices that require to be exhausted.

In the example shown in Fig. 1, the air ejector comprises a pipe or casing *f* adapted

to be connected to a condenser by the branch *a* through which the mixture of air and vapor is withdrawn, and provided with a steam nozzle *s* arranged to discharge a jet of steam into the interior *f* of such pipe or casing *f* through a tube *g*; a water spraying and steam condensing device *h* having orifices *x* for the discharge of water spray, and a solid water jet nozzle *j* delivering into a combining cone *f*, the said orifices *x* and nozzle *j* being arranged in parallel with each other within the spraying chamber *f* of the casing *f* so as to discharge water simultaneously in parallel streams. Another water jet nozzle *j* of the annular type is arranged coaxially with or in combination with the water spraying, steam condensing device *h* and water jet nozzle *j* and discharge pipe *e*, the steam nozzle *s*, the water spraying and condensing device *h* together with the water jet nozzle *j* and annular water jet *j* being provided with separate controlling means or valves *k*, *l*, *m* respectively, so that each can be separately regulated or shut off in order to effectively deal with the varying quantities of air in the condenser. The cross sectional area of the water passage through the water jet nozzle *j* may be varied by a tube *j* that can be adjusted in an endways direction by an eccentric device *n* that engages a recessed boss *j* on the tube *j* and is operated by a hand wheel *p*. A non-return valve *a* may also be provided, such valve, in the form of a float, acting, should water rise in the casing *f*, to automatically close the tube *g* and so prevent water reentering the condenser through the branch *a*.

It has been found by experiment, that in the case where a steam nozzle is provided in connection with the air ejector, that when the condensing system is exceptionally air tight, or when the water jets are alone sufficient to dominate the condenser, at the desired vacuum, and the steam to the steam jet is shut off, that the flow of air and vapor through the tube *g* into which the steam jet discharges, may become throttled by reason of the comparatively small diameter of such tube. In order to obviate such detrimental effect, the apparatus may be provided with a by-pass pipe *a* of adequate cross sectional area, such by-pass pipe being fitted with a valve *v* which is closed when the amount of air justifies the use of the steam jet *s*, and opened when the steam jet is out of use.

B is a tank into which the air ejector discharges and t is a pump, for example a centrifugal pump, by which water is withdrawn from the tank and delivered through 5 a pipe t^1 to either or both of the two branches of the air ejector controlled by the valves l, m .

With the arrangement described, the supply of steam to the steam nozzle s and of 10 water to the water spraying device h and central nozzle j^1 , or to the water jet device j , can be separately regulated so that steam can be supplied to the steam nozzle and water to the water spraying device and water 15 jet device or to one of these devices, or the steam can be shut off and water supplied to the water jet device only, as may be required to satisfactorily deal with the amount of air present in the condenser at the particular 20 vacuum desired.

In Fig. 2, the water spraying device h consists of an annular water chamber arranged above and independent of the central nozzle j^1 and provided with an annular 25 row of orifices or nozzles x . s^2 is a water ejecting nozzle fed from the pump t through the pipe t^1 and which withdraws water from the condenser through the pipe a and discharges it through a pipe b^1 into 30 the spraying chamber h whence it escapes through the spraying orifices x as already described, water being supplied separately to the nozzle j^1 through the valve m^1 . In some cases the steam nozzle s may be omitted, the air ejector being worked by water 35 alone supplied thereto under pressure. Also, the central water jet nozzle j^1 may in some cases be omitted.

What I claim is:—

40 1. An air ejector comprising, in combination, a chamber having at one end an inlet passage for air and at the other end a combining cone and a discharge pipe leading therefrom, a water chamber provided with 45 apertures through which multiple jets of condensing water can enter said casing, a nozzle having its discharge end terminating within said combining cone and through which a solid jet of water can be forced and 50 caused to enter the combining cone as a solid jet of water and discharge the condensing water and admixed air from said chamber through said combining cone and discharge pipe and a final water jet nozzle surrounding 55 the combining cone and adapted to discharge an annular stream of water into said discharge pipe at a point beyond the combining cone.

2. An air ejector comprising, in combination, a chamber having a gradually contracted lower end portion with a discharge pipe extending downward therefrom and at the top an upwardly extending inlet pipe of less cross sectional area than the chamber 65 at its widest part, an air and vapor inlet

branch connected to but of greater cross sectional area than said inlet pipe, a steam nozzle arranged to direct a jet of steam into said inlet pipe so that said jet will mingle with the air coming from said inlet branch and within the inlet pipe, a water chamber having apertures through which a number of jets of condensing water can enter said chamber below said inlet pipe and mingle with the mixed air and steam in said chamber and condense the steam and a water jet nozzle arranged centrally in said chamber and terminating at its lower end in the lower contracted end portion of said chamber so that a practically solid jet of water will issue into the said lower contracted end portion of the chamber and eject the mixture of condensing water, air and water of condensation falling into said lower end portion of the chamber through the discharge pipe into the external atmosphere.

3. An air ejector comprising, in combination, a chamber having a gradually contracted lower outlet end portion and a discharge pipe into which said outlet end portion discharges, an inlet pipe connected to the upper end of said casing and of smaller cross sectional area than the largest cross sectional area of said chamber and an air inlet branch connected to the upper end of 90 said inlet pipe and of greater cross sectional area than said inlet pipe, a steam nozzle arranged to direct a jet of steam into said inlet pipe, a water chamber having a number of apertures through which jets of condensing water can enter said casing below the inlet pipe, a centrally arranged water nozzle terminating in the lower contracted outlet end portion of said casing and through which a solid jet of water can be forced 95 through the combining tube, a centrally arranged vertically adjustable tube arranged to extend into the inlet of said discharge pipe and form an annular outlet passage therewith and means for manually adjusting said tube in an axial direction from the side of said casing whereby the cross sectional area of said passage can be varied.

4. An air ejector comprising, in combination, a casing having an inlet pipe at one end and a combining cone and discharge pipe at the other end, said inlet pipe terminating in an air inlet branch of greater cross sectional area than the inlet pipe, a steam nozzle arranged to discharge a jet of steam into the inlet end of said inlet pipe, a water chamber provided with apertures through which multiple jets of water can issue into said casing at a part thereof beyond said steam nozzle and inlet pipe, a nozzle terminating in the combining cone and through which a solid jet of water can issue and pass through said combining cone as a solid jet and discharge the mixture of air and water coming from the upper part of the 100 110 115 120 125 130

chamber through the combining cone into said discharge pipe, and a water jet nozzle arranged around and external to the combining cone so as to discharge an annular stream of water into said discharge pipe at a point beyond the end of the combining cone.

5. An air ejector comprising, in combination, a casing having at one end an inlet for air, a condensing chamber with discharge pipe in advance thereof and a connecting passage between said air inlet and chamber and of considerably smaller cross section than either of these parts, a steam nozzle 10 for ejecting steam into said passage so as to mingle with the air coming from the inlet and within the passage, means for causing jets of condensing water to enter into said chamber, and a by-pass pipe with controlling valve between said air inlet and condensing chamber, said by-pass pipe being of larger cross sectional area than said connecting passage and through which air can freely flow when the controlling valve is 15 open and the steam nozzle closed.

6. A water operated air ejector comprising, in combination, a condensing chamber having an uncontrolled main inlet pipe for air and an outlet pipe for air and water, a steam nozzle for directing a jet of steam 20 into said inlet pipe, means for directing jets of water into said chamber, a downwardly extending discharge pipe in communication with the outlet from said chamber and an automatic float valve located in said chamber and adapted to rise and automatically close the communication between said inlet pipe and chamber upon the steam and water supply being cut off and water rising 25 through said discharge pipe sufficiently high within said chamber to lift said valve.

7. An air ejector comprising, in combination, a casing having an air inlet branch and an air and water discharge pipe, an enlarged intermediate condensing chamber of curvilinear section terminating at its forward end in a combining cone, a connecting passage between said inlet branch and condensing chamber of considerably smaller 30 cross section than either of these parts, a water chamber surrounding said combining cone so as to form therewith an annular water nozzle through which an annular jet of water will enter the discharge pipe at a 35 point beyond said combining cone, and

water inlet branches, one of said branches being in communication with said water chamber, a valve controlled steam nozzle arranged to discharge a jet of steam directly into said connecting passage so that such 40 steam mingles with the air coming from the inlet branch and within the connecting passage, a water chamber arranged within said condensing chamber and in communication with another of said water inlet branches 45 and provided with apertures through which jets of water can issue into said chamber beyond the connecting passage and steam nozzle and condense the steam in the mixture of air and steam within said chamber and a 50 centrally arranged water nozzle extending from said water chamber and terminating within said combining cone and through which a solid jet of water can be discharged into and through the combining cone for the 55 purpose herein set forth.

8. An air ejector comprising, in combination, a condensing chamber having at one end an inlet passage terminating at its inlet end in an air inlet branch of much larger 60 cross sectional area than the passage, and at the other end a combining cone and discharge pipe, a steam nozzle arranged to discharge a jet of steam into the inlet end of said inlet passage so as to mingle with the 65 air coming from the said inlet branch and within the said passage, a water chamber arranged within the said condensing chamber and provided with apertures through which jets of water can issue into said casing at a 70 part thereof beyond said inlet passage and steam nozzle and condense the steam in said chamber and a final water jet nozzle comprising a water chamber surrounding the combining cone and in communication with 75 said discharge pipe and through which an annular stream of water can be discharged into said discharge pipe at a point beyond the termination of said cone, so as to force the mixture of air and water coming from 80 the condensing chamber into and through said discharge pipe, all substantially as herein described and shown.

Signed at Hartlepool, England, this thirteenth day of September 1910.

DONALD BARNS MORISON.
